UNITED STATES PATENT OFFICE.

M. FRANK McNELLY, OF STERLING, ILLINOIS.

MINING-MACHINE.

SPECIFICATION forming part of Letters Patent No. 356,488, dated January 25, 1887.

Application filed April 12, 1886. Serial No. 198,538. (No model.)

To all whom it may concern:

Be it known that I, M. FRANK McNELLY, a citizen of the United States, residing at Sterling, in the county of Whiteside and State of Illinois, have invented certain new and useful Improvements in Rock and Coal Drills; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention has reference to rock or coal drills, and pertains more especially to certain mechanism, hereinafter described, more particularly adapted to drilling for blasts in coal-mines and like situations where the room for 20 working machinery is limited, and where the drilling is required to be done at various altitudes and in various directions.

In the drawings, Figure 1 is a side elevation. Fig. 2 is a section in line xx of Fig. 1. Figs. 25 3, 4, and 5 are detail views. Fig. 6 is a top view of the nut which holds the auger. Figs. 7 and 8 are partial plan views of the auger and its connections. Fig. 9 is an elevation. Fig. 10 is a section in line yy of Fig. 7. Fig. 30 11 is a plan of my attachment for driving the auger. Fig. 12 is a cross-section in the line zz of Fig. 11. Fig. 13 is a detail cross-section on the line $z'z'$ in Fig. 11, showing the feather K' in position.

35 A A are parallel vertical tubes suitably united at their lower ends to a common central pivotal base, A^2 , and open at their upper ends.

B B are parallel round rods or bars united at their upper ends into a pivotal central point, 40 B^2 , and adapted to have their lower ends enter and be adjustable within the tubes A A. Set-screws C C, seated in the respective walls of the tubes A A, and having their compressing end in contact with the exterior of the 45 bars B, serve as means of such adjustment.

D is a cross-bar having the round central vertical hole D' , and vertical end sockets, D^2 , through which latter are placed the tubes A, respectively. The cross-bar D constitutes the 50 seat for the auger, and is adjustable to different altitudes by shifting vertically on the

tubes A, being held at any desired height by set-screws D³, seated in the walls of the sockets D², and adapted to be screwed against the outer walls of such tubes.

55

E is a shear swivel consisting of two upwardly-extending jaws, E', mutually hinged at their lower ends and rounded into the stem E², which latter is seated pivotally in and conforms to the central hole, D', in the cross-bar D. 60 The stem E² has an annular recess, E⁴, engaged by a horizontal set-screw, E⁵, which holds such stem from withdrawal but permits its lateral rotation in the hole or socket D'.

F is the seat of the auger G, and consists of 65 an open nut having lateral trunnions F', which enter and are pivotally supported in the transverse holes E³ in the upper ends of the jaws E' of the swivel E. The upper and lower halves of the seat F are hinged together at F², 70 and at their opposite ends overlap and are held by the removable pin F³. The auger G has its shank threaded to correspond with the threads in the nut F, and in its rotation is thereby advanced.

75

At the upper ends of the rods A is centrally seated the vertical stationary nut A', in which is seated a threaded bar, H, having lateral handles, and adapted to be screwed up against the roof, so as to hold the machine in position. 80 A crank, J, is attached to the outer end of the shank of the auger G as a means of rotating the latter; but as it often happens that a blast is required at a point or in such direction that it is impracticable to operate the auger at the 85 end for lack of crank-room, I obviate this difficulty by the provision of the following-described side attachment.

K is a frame in which are journaled at right angles to each other the engaging small bevel-pinion K' and large bevel-pinion K². The axle K³ of the latter is hollow, and is adapted to slip loosely on the auger G.

90

At one end of the frame K is formed the equal-sided socket K⁴, which is passed over an 95 equal-sided projection, F⁴, on the outer end of the nut or auger-seat F, and fastened therein by the set-screw K⁵. The outer end of the axle K⁶ of the small drive-pinions K' is fitted to receive the crank J. A feather, K⁷, on the 100 inner wall of the axle K³ of the larger pinion, engages a longitudinal groove, G', in the shank

G^3 of the auger G , and thereby the rotation of the axle K^6 is communicated to the auger G , the feather K^1 traversing the groove G' and permitting the progress of the auger G . The 5 auger-bit G^5 is attached to its shank G^3 by means of a U-shaped socket, G^4 , in the latter, the inner end of the bit being shaped to enter and conform to such socket, whereby oscillation in any direction is prevented.

10 The advantages of my invention are as follows: The side driving mechanism described is not only applicable in diagonal drilling, where the outer end of the auger-shank is too near the sides, floor, or roof to permit the crank 15 to be used in the end of the auger-shank and the power increased by such side mechanism, but the socket K^4 and projection F^4 being square and equal-sided, the auxiliary driving mechanism can be attached above, below, or 20 on either side of the auger G , as may be necessary or preferable. The threads within the nut F extend also throughout the projection F^4 , and thus increase the strength of the nut and prevent the breaking of the threads on 25 the nut or the auger. The projection F^4 is in two parts, each of which is integral with the halves of the nut F , and the socket K^4 also holds the said nut together in case of the casual withdrawal of the pin F^3 . A further advantage is in having three pivotal bearings, to wit, the extremities of the machine, the central vertical socket, D' , of the bar D , and the trunnions F' of the nut F , whereby the tubes A may be set nearly in line with the hole to be 30 drilled and the auger projected obliquely between them in such line, and the boring therefore be done close to the side of the drift. The machine may be set at any angle. By adjusting the bars B within the tubes A a compact and simple mode is provided for lengthening or shortening the machine without the inconvenience of extra pieces.

35 What I claim as my invention, and desire to secure by Letters Patent of the United States, 40 is—

1. The combination of the tubes A A , provided with common central base, A^2 , the bars B B , inserted, respectively, in said tubes, the set-screws C C , seated, respectively, in the walls of the tubes A and adapted to press 50 against the bars B , so as to hold the latter adjustably within said tubes, the stationary nut A' , the threaded bar H , seated in nut A' , the cross-bar D , provided with central hole, D' , and end sockets or holes, D^2 , through which latter are respectively passed the tubes A , set-screws D^3 , seated in the walls of the sockets D^2 , and adapted to be screwed against the exterior of said tubes, the swivel E , provided with jaws E' and stem E^2 , and adapted to be 60 seated pivotally in the hole D' , the inwardly-threaded open nut F , provided with lateral trunnions F' , pivotally seated, respectively, in the holes E^2 of the jaws E' , and the auger G , seated pivotally in the nut F , whereby said 65 auger can be shifted laterally, vertically, or obliquely, substantially as shown, and for the purpose described.

2. The combination, of the auger-seat F , provided with the angular projections F^4 , the 70 auxiliary frame K , provided with socket K^4 , adapted to be seated on projections F^4 , the bevel-pinion K' , the axle K^6 of pinion K' , journaled in frame K , crank J , attached to axle K^6 , pinion K^2 , engaged and driven by pin- 75 ion K' , axle K^3 of pinion K^2 , adapted to slip on shank G^3 of auger G , and provided with internal feather, K^1 , to engage the groove G' of shank G^3 , and the auger G , provided with shank G^3 and groove J' therein, substan- 80 tially as shown, and for the purpose described.

In testimony whereof I affix my signature in presence of two witnesses.

M. FRANK McNELLY.
